HANDBAG

William H. Hardy, River Edge, N. J.

Application September 14, 1951, Serial No. 16,642

Term of patent 3½ years

(Cl. D87—3)

To all whom it may concern:

Be it known that I, William H. Hardy, a citizen of the United States, residing in River Edge, in the county of Bergen and State of New Jersey, have invented a new, original, and ornamental Design for a Handbag, of which the following is a specification, reference being had to the accompanying drawing, forming part thereof.

Fig. 1 is a front perspective view of a handbag showing my design with the lid in raised position;

Fig. 2 is a rear perspective view of the handbag shown in Fig. 1, in closed position;

Fig. 3 is a front elevational view of the handbag shown in Figs. 1 and 2; and

Fig. 4 is a side view thereof.

I claim:

The ornamental design for a handbag, substantially as shown.

WILLIAM H. HARDY.
